Primary Examiner — Dana Meyrow(74) Attorney, Agent, or Firm — Kirschstein, Israel, Schiffmiller & Pieroni, P.C.(57) CLAIM

The ornamental design for a bottle, as shown and described.

DESCRIPTION

FIG. 1 is a side elevation view of a bottle according to my new design, the opposing side elevation view being identical excluding the unclaimed thread element;

FIG. 2 is a top plan view thereof; and,

FIG. 3 is a bottom plan view thereof.

The broken lines in the drawings illustrate the portions of the bottle that form no part of the claim.
